(57) **CLAIM**

The ornamental design for a battery termination, as shown.

DESCRIPTION

FIG. 1 is a perspective view of the battery termination according to the present invention.

FIG. 2 is a top view of the battery termination shown in FIG. 1, having a front edge oriented to the bottom of the page.

FIG. 3 is a front view of the battery termination shown in FIG. 1.

FIG. 4 is a left side view of the battery termination shown in FIG. 1.

FIG. 5 is a right side view of the battery termination shown in FIG. 1.

FIG. 6 is a rear view of the battery termination shown in FIG. 1; and,

FIG. 7 is a bottom view of the battery termination shown in FIG. 1.
